FIG. 1

FIG. 2

FIG. 3

FIG. 4

FIG. 5

FIG. 8

FIG. 1 is a rear perspective view of a combined dispenser for moist throwaway towelettes and mounting bracket therefor, showing my new design;

FIG. 2 is a front perspective view thereof with the lid raised;

FIG. 3 is a top plan view thereof;

FIG. 4 is a rear elevational view thereof;

FIG. 5 is a view similar to FIG. 2 but with the whole cover raised;

FIG. 6 is a view similar to FIG. 2 but with the lid lowered and the mounting bracket removed for ease of illustration;

FIG. 7 is a view similar to FIG. 1 again with the mounting bracket removed for convenience of illustration; and

FIG. 8 is a front elevational view with the lid raised, taken somewhat from above.

The bottom of the dispenser and the bottom of the mounting bracket are both plain.

I claim:

The ornamental design for a combined dispenser for moist throwaway towelettes and mounting bracket therefor, as shown and described.
